Primary Examiner — Clare E Heflin(74) *Attorney, Agent, or Firm* — Calfee, Halter & Griswold LLP(57) **CLAIM**

I claim the ornamental designs for a lighting fixture, as shown and described.

DESCRIPTION

The sole FIGURE is a front perspective view of a lighting fixture. This fixture has mirror image symmetry (one hundred eighty degree overall rotational symmetry, and mirror image symmetry along a first vertical imaginary plane and also mirror image symmetry along a second vertical imaginary plane, with the first and second vertical imaginary planes being orthogonal to each other). The shades each have a circular horizontal cross-section.

The broken lines shown in the drawing are for illustrative purposes only and form no part of the claimed design.
